United States Patent

Des. 240,873
Patented Aug. 10, 1976

240,873

FOLDING CHAIR

Robert D. Lewis, 1121 Aberdeen, Apt. A, Harvey, La.
70058, and Daniel G. Goss, 2313 Hero Drive, Gretna,
La. 70053

Filed Dec. 30, 1974, Ser. No. 537,545

Term of patent 14 years

Int. Cl. D6—01

U.S. Cl. D6—76

FIG. 1

FIG. 2

FIG. 3

FIG. 4

FIG. 1 in the drawings depicts a side elevation view of the present folding chair taken from a left side position showing the present chair in an operable unfolded normal use position.

FIG. 2 in the drawings represents a side elevation view of the present folding chair taken from a left-side position showing the present chair in a folded up arrangement.

FIG. 3 in the drawings represents a top plan view of the present folding chair showing it in the operable position as depicted in FIG. 1.

FIG. 4 of the drawings depicts an isometric view of the present folding chair taken from a right-front position.

I claim:

The ornamental design for a folding chair, as shown.
